TOY VEHICLE CHASSIS

Carl A. Swenson, 615 N. Berlyn Ave.,
Ontario, Calif. 91764

Filed July 19, 1971, Ser. No. 164,211

Term of patent 14 years

Int. Cl. D21—01

U.S. Cl. D34—15

FIG. 1 is a right front perspective view of a toy vehicle chassis showing my new design;

FIG. 2 is a top plan view thereof;

FIG. 3 is a left side elevational view thereof;

FIG. 4 is a bottom plan view of FIG. 3;

FIG. 5 is a front elevational view of FIG. 1; and

FIG. 6 is a rear elevational view thereof.

I claim:

The ornamental design for a toy vehicle chassis, as
